WELL FLOWING MEANS

Raymond G. Taylor, Jr., and Edgar D. Wilde,
Dallas, Tex., assignors to The Guiberson Corporation, Dallas, Tex., a corporation of Delaware

Application January 22, 1942, Serial No. 427,704

9 Claims. (Cl. 103—231)

This application is a continuation, in part, of the application filed by the applicants on December 6, 1941, in the United States Patent Office for Well flowing means, Serial No. 421,890.

In the said application 421,890 there was described a means whereby oil in the casing could be initially unloaded by passing compressed gases into the tubing from the surface of the ground with means to pass this compressed gas from the tubing into the casing and thereby unload it. There was also shown a wire line valve below the above mentioned means, and after the oil in the casing had been unloaded, the compressed gas could be conducted into the casing, and when the wire line valve was open, the compressed gas would pass from the casing into the tubing to lift the oil in the tubing to the surface. However, in unloading the oil in the casing, some of it would adhere to the casing and would gradually drain back into the lower portion of the casing and might cover the wire line valve to a considerable depth. One of the objects of this invention is to provide a conductor extending upwardly in the casing from the wire line valve to a height above the level which would be reached by the oil in the casing after it drains back after the major portion of the oil therein has been unloaded.

Another object of the invention is to provide an improved wire line operated valve.

Other objects and advantages of the invention will appear in the detailed specification and claims which follow. The invention may be better understood by referring to the attached drawings.

Figure 1 is a view partly in elevation and partly in cross section showing the upper portion of a well with the surface connections;

Figure 2 is a view similar to Figure 1 of the parts below Figure 1, Figure 2 being a continuation of the lower portion of Figure 1;

Figure 3 is a transverse view, partly in cross section and partly in elevation, of the parts below Figure 2, Figure 3 being a continuation of the lower portion of Figure 2 and showing the parts at the bottom of the well;

Figure 4 is an enlarged cross-sectional view of one of the check valves, the movable part of the valve being shown in elevation;

Figure 5 is an enlarged view of the wire line valve shown in Figure 3, certain of the parts being shown in cross section, and the remaining parts being shown in elevation; and

Figure 6 is a cross-sectional view on the line 6—6 of Figure 5, except that the movable valve member is shown as a plan view.

Referring to the drawings in detail, a pressure fluid supply pipe 1 extends to a T 2 from whence a pipe 3 extends to the casing 8, there being a shut-off valve 7 interposed in the pipe 3.

Also, extending from the T 2 is a pipe 4 leading to the tubing 5, there being a shut-off valve 6 interposed in the pipe 4. An eduction pipe 11 provided with a valve 12 extends from the casing 8 to a T 14. An eduction pipe 9 extends from the flow line 5 to the T 14, said eduction pipe 9 being provided with a shut-off valve 10. The T 14 is connected to a pipe 13 leading to a fluid reservoir (not shown) where the oil would be stored.

At spaced points in the tubing 5 are check valves 15, one of these check valves being shown in detail in Figure 4. An elbow nipple 16 is attached to the tubing so that the hollow portion 15 of the nipple communicates with a hole 17 in the tubing. Secured to the upper end of the nipple 16 is a connection 18, and its upper end is provided with a valve seat 22. The housing 15 of the check valves is secured to the upper end of the connection 18 and is provided with radially extending ports 20. A lug 21 is provided above each of the valves to prevent the valves being knocked off when the tubing is pulled from the well. The housing 15 is hollow providing a chamber 19 in which a valve plunger 21 is movable, the lower end of the plunger 21 being tapered, forming a valve to seat against the valve seat 22. The members 16 and 18 are hollow so as to form a passageway from the ports 20 to the hole 17 when the valve plunger 21 is raised from the seat 22. The upper portion of the chamber 19 is closed by a plug 25, which is provided with a radially extending port 26 communicating with a downwardly extending channel 26', which extends from the port 26 to the chamber 19.

If oil should be standing in the casing above the check valves, and if the valves 12 and 6 were opened and the valves 7 and 10 were closed, compressed gas from the pipe 1 could pass downwardly through the tubing and into the casing, thence through the hole 17 in the tubing and upwardly through the hollow portions of the elbow 16 and connection 18, raising the valve plunger 21 and allowing the compressed gas to pass outwardly through the ports 20 into the oil in the casing where it would be raised into the pipe 11 and would flow to the reservoir through the pipe 13. This would unload the oil in the casing.

Below the check valves and secured to the tubing is a wire line valve 29 including a housing 30, and below the housing the tubing 5 continues downwardly. The valve housing is provided with a bore 31 communicating with the interior of the tubing. Projecting into the bore is a valve 32 which slides in valve guide 33. The valve is provided with a flaring valve portion 34, which is urged towards the seat 35 by means of the spring 37, which extends between the valve

portion 34 and the cap 36. This cap 36 may be provided with holes 74 for a spanner wrench, so that the same may be easily inserted or removed. Between the cap 36 and the outer portion of the valve guide 33 is a recess 35, which communicates with a bore 41 in the valve housing 30, which in turn communicates with an upwardly extending pipe 52, which is held to the tubing by means of clamps 53. The pipe 52 extends upwardly a sufficient distance so that after the well casing is unloaded, any oil which clings to the casing or which may not be ejected will not form a level above the upper end of the open pipe 52, the object being that when compressed air is later introduced into the casing, as will hereinafter be described, this compressed air can pass directly into the upper end of the pipe 52 and downwardly therethrough without having to break through a column of oil.

The valve 32 is provided with a tappet 38, the inner portion, or the part which extends within the chamber 31, being substantially hemispherical. The part of the valve 32 between the tappet 38 and the flaring valve portion 34 is of reduced size, so as to leave a chamber 73 between this reduced portion and the valve guide 33. The valve guide 33 is also provided with ports 72 communicating with the chamber 73 and with a recess 42 in the valve housing which, in turn, communicates with a downwardly extending passageway 43 leading to a pipe 44, which communicates with a passageway 46 in a packer head 45 which carries a packer 28 to seal the space between the packer head and the casing 8. The lower end of the tubing 5 also is screwed into the upper central portion of the packer head 45, so that the packer 28 and packer head 45 prevent oil from passing upwardly from the sands to the space between the tubing and casing, and likewise prevents compressed air, which may be introduced into the casing, from exerting its pressure downwardly on the oil at the bottom of the well and below the packer 28. The packer head 45 is provided with a chamber 47 which communicates with the passageway 46. An enlarged case 48 is screwed to the lower end of the packer head 45 and its interior communicates with the chamber 47, the interior of the case 48 forming a chamber 49. The lower end of the case 48 is provided with the usual standing valve 50 and fluid inlets 51.

A wire line passes downwardly through the tubing and carries at its lower end a weight 39, preferably having its upper end cone-shaped and adapted to actuate the tappet 38 of the wire line valve and to press it outwardly against the tension of the spring 37 when the wire line is raised by any suitable mechanism above the ground. A stop 55, preferably in the form of a grate, is positioned in the lower portion of the tubing and at a distance below the wire line valve 29 slightly in excess of the effective length of the weight 39. The spaces between the grating allow the oil to pass upwardly into the tubing. The object of the stop 55 is to eliminate the necessity of a wire line meter. The weight 39 can be lowered in the well until its downward travel is stopped by the stop 55, and the operator then knows that it is necessary for the weight to be lifted only a short distance in order to open the wire line valve.

After the oil in the casing has been unloaded, as above described, oil will pass upwardly through the standing valve into the chamber 49 and into the lower end of the tubing, where it will rise to a certain standing level, there being no oil in

the casing above the upper end of the pipe 52. If now the valves 7 and 10 are opened and the valves 6 and 12 are closed, compressed gas will pass from the pipe 4 into the casing, and downwardly through the pipe 52 to the outer portion of the flaring valve portion 34, where it will be stopped when the valve is seated, or is in the position shown in Figures 3, 5 and 6. If, however, the wire line be raised so that the tappet 38 is pressed outwardly, the flaring valve portion 34 would be moved away from its seat 75, and the compressed gas passing downwardly through the pipe 52 and passageway 41 will pass around the wire line valve through the ports 72, recess 42, passageway 43, pipe 44, passageway 46, chamber 47 and into the chamber 49. It will then pass downwardly around the lower end of the tubing and upwardly through the stop 55 to aerate the oil in the tubing and cause it to be ejected upwardly through the tubing to the eduction pipe 9 and to the fluid reservoir through the pipe 13. As soon as the weight is lowered, the spring 37 causes the wire line valve to close and the above described passage of the compressed air is stopped. Any air which may be trapped in the chamber 49 or in the passageways between said chamber and the wire line valve can now bleed off into the tubing through the chamber 73 and bleeder port 54.

As will be noted from inspecting Figure 3, the bore 31 is offset from the passageway through the tubing 5 so that the weight will be forced into contact with the tappet 38 while providing ample space for the upper passage therethrough of any fluid such as oil or gas.

In this specification and claims forming a part thereof, a wire line valve is intended to cover a valve operated by a weight on a wire line and is not intended to cover a valve supported by and bodily movable upwardly and downwardly with the upward and downward movement of the wire line.

We realize that many changes may be made in the form of invention as is described by way of illustration herein without departing from the spirit of the invention. We, therefore, desire to claim the same broadly, except as we may limit ourselves in the appended claims.

Having now described our invention, we claim:

1. In combination with a casing and a tubing having a chamber therebetween, a valve leading from the tubing into said chamber, means whereby compressed gas may be admitted into said tubing and through said valve to unload the oil in said chamber, a second valve in said tubing below said first valve and leading from the chamber into the tubing, a pipe extending from said second valve to a point in said chamber above the oil level which may be formed by oil which may not have been ejected from the casing when unloading, and means whereby compressed gas may be admitted into the casing and downwardly through said pipe to said second valve and through said valve when opened into the tubing to expel the oil therefrom.

2. In combination with a casing and a tubing having a chamber therebetween, a valve leading from the tubing into said chamber, means whereby compressed gas may be admitted into said tubing and through said valve to unload the oil in said chamber, a second valve in said tubing below said first valve and leading from the chamber into the tubing, a pipe extending from said second valve to a point in said chamber above the oil level which may be formed by oil which may not have been ejected from the casing when

unloading, and means whereby compressed gas may be admitted into the casing and downwardly through said pipe to said second valve and through said second valve when opened into the tubing to expel the oil therefrom, and means to control said second valve.

3. In combination with a casing and a tubing having a chamber therebetween, a valve leading from the tubing into said chamber, means whereby compressed gas may be admitted into said tubing and through said valve to unload the oil in said chamber, a wire line operated valve in said tubing below said first valve and leading from the chamber into the tubing, a pipe extending from said wire line valve to a point in said chamber above the oil level which may be formed by oil which may not have been ejected from the casing when unloading, and means whereby compressed gas may be admitted into the casing and downwardly through said pipe to said wire line operated valve and through said wire line operated valve when opened into the tubing to expel the oil therefrom.

4. In combination with a flow line and a casing having a compressed gas chamber therebetween, a check valve on the flow line to prevent passage of compressed gas from the chamber into the flow line while allowing gas or oil to flow therethrough from the flow line to the chamber and to be ejected therefrom by the gas introduced into the chamber, a wire line valve on the flow line below the check valve and serving as a means to intermit through the flow line, and a conduit extending from the wire line valve and opening into the chamber at a point above the oil level which may be formed in the chamber by oil which may drain back into the lower portion of the chamber after the bulk of said oil has been ejected.

5. In combination with a flow line and a casing having a compressed gas chamber therebetween, a check valve on the flow line to prevent passage of compressed gas from the chamber into the flow line while allowing gas or oil to flow therethrough from the flow line to the chamber and to be ejected therefrom by the gas introduced into the chamber, a wire line valve on the flow line below the check valve and serving as a means to intermit through the flow line, and a conduit extending from the wire line valve and opening into the chamber at a point above the position of the check valve.

6. In combination with a flow line and a casing with a chamber therebetween, means to admit pressure gas into the flow line, a check valve in said flow line through which oil in the flow line may be forced from the flow line into the chamber by the pressure gas in the flow line and when the oil level in the flow line has been reduced to the level of said check valve, said pressure gas will pass from said flow line into the chamber to expel the oil in said chamber above the check valve, a second valve in the flow line below the check valve, means to admit pressure gas into the chamber and cut off the pressure gas to the flow line, means to operate said second valve to admit gas from the chamber into the flow line, and a conduit extending from the second valve and opening into the chamber at a point above said check valve.

7. In combination with a flow line and a tubing with a compressed gas chamber therebetween, a check valve in said flow line through which oil in the flow line may be forced from the flow line into the chamber by the pressure gas in the flow line and when the oil level in the flow line has been reduced to the level of said check valve, said pressure gas will pass from said flow line into the chamber to expel the oil in said chamber above the check valve, a wire line valve extending into the flow line and serving as a means to introduce compressed gas from the chamber into the flow line when the wire line valve is open, a reciprocatable wire line, means on said wire line to engage that part of the wire line valve extending into the flow line to open said wire line valve, and a conduit extending from said wire line valve and opening into said chamber at a point above said check valve so as to provide a passage through any liquid which may be in the lower portion of the chamber.

8. In combination with a flow line and a tubing with a compressed gas chamber therebetween, a valve member having a knob extending into the flow line and a valve spaced therefrom and having a reduced shank connecting said knob and valve, a housing for said valve and provided with a valve seat for said valve, said housing providing a valve chamber between the shank and the housing, a passageway leading from the said valve chamber to the flow line, a passageway from the valve chamber to the compressed gas chamber which passageway is opened or closed by said valve, a wire line, means on said wire line to open said valve and thereby permit the gas in the compressed gas chamber to pass through the passageway from the compressed gas chamber to the valve chamber and thence to the passageway leading to the flow line, and a spring to close said valve when the wire line is operated to remove the said means from contact with the said knob, and a by-pass leading from the chamber into the tubing when the valve is closed so that any compressed gas trapped in the passageway between the valve chamber and the flow line may bleed off into the tubing, said knob serving as a means to close said by-pass when the valve is open.

9. A valve assembly including a housing having a valve chamber therein, said housing being provided with a valve seat at one end of said chamber, a valve member slidably in said valve chamber, said valve member comprising a valve, a knob and a shank connecting the valve and knob, passageways leading to and from said valve chamber, a spring tending to hold said valve on its valve seat to close said passageway leading to the valve chamber, said knob serving as a means to operate said valve and open said passageway leading to the valve chamber so that the fluid may flow from the passageway leading to the valve chamber and through the said chamber to the passageway leading from the valve chamber, said housing being provided with a bleeder port leading from said valve chamber around said knob when the valve is closed, said knob closing said bleeder port when the valve is opened.
